United States Patent Office.

JOSEPH W. BAILEY, OF NEW ORLEANS, LOUISIANA.

Letters Patent No. 81,579, dated September 1, 1868.

IMPROVEMENT IN MARKING WEATHER-BOARDING.

The Schedule referred to in these Letters Patent and making part of the same.

TO ALL WHOM IT MAY CONCERN:

Be it known that I, JOSEPH W. BAILEY, of the city of New Orleans, parish of Orleans, and State of Louisiana, have invented a certain new, useful, and improved Mode of Indicating the Overlapping Line of Weather-Boards, by marking the said line in a novel way; and I do hereby declare the following to be a full, clear, and exact description of the same, reference being had to the annexed drawings, making a part of this specification, and which represent front and end views of two weather-boards, as marked by my method.

In order that the great value and importance of my invention shall be fully comprehended, it is only necessary to advert to the fact that, in the operation of putting on weather-boarding, as now universally practised by carpenters and joiners, that part of each board that is to be exposed, or "shown to the weather," as mechanics express it, has always to be measured and marked by hand. This is sometimes done just before the board is put into its place on a wall; but usually, the board is nailed to its place first, and the admeasurement is made afterwards. In either case, the admeasurement and the marking consume far more time than is required to nail or fasten the board upon the wall. Gauges, especially constructed and adapted to the purpose, are the implements commonly employed to indicate the proper admeasurement, and thus to secure a uniform width of exposure as to each and every board. But inasmuch as no admeasurement, as a general thing, is ever made, excepting only at the two ends of the boards, uniformity is only secured throughout the whole length of the same when the boards are perfectly straight upon their lower edges. If a board be sprung edgewise, as is nearly always the case, to a greater or less extent, the gauge has to be applied at its middle, or the result will be great irregularity of width; and if the lap be very slight or narrow, it not unfrequently happens that the very integrity of the wall is destroyed by openings between the boards.

My invention saves all the time lost in the above-described way, and secures perfectly-straight lines as to the edges of every board, and hence uniformity of width at every point, from one end of them to the other.

It consists simply of a marking of the boards, along the line at which the lower edge of the next superior board is to be placed; either as they are being sawed out of the log, or afterwards, when they are being planed, by means of any proper tool for making a groove or other plainly-visible inscription, longitudinally, which tool is connected with the saw-mill or the planing-machine, as the case may be; or, instead of a groove or other equivalent impression, when the mark is made in the operation of planing, a raised line may very easily be substituted, by a slight gap or notch in the cutters of the machine; or it may sometimes be expedient to make the mark consist of the lower edge of a bevel that is cut in the act of planing the board.

I do not deem it necessary to describe any particular mechanical means or device for making the mark, nor my particular arrangement for the effective adaptation or application of the same to the fulfilment of the prescribed object, because I wish it distinctly understood that, whilst I lay no claim to the exclusive use of any proper means for inscribing or producing the mark, nor for any special mode of applying such means, I reserve the liberty, which is my right, of employing any sufficient means, and to employ them in any effective manner, by any usual arrangement or application. My invention does not refer to the means or instrumentalities for producing a mark, but it is the marking itself that establishes its value.

The mark may consist of a series of punctures or dots, as shown at fig. 1, extending from one end of the boards to the other; or of a continuous groove, thus extending; or of a number of short grooves, with unmarked spaces between them. Any mark will answer that is deep enough not to be obliterated by the planing of the boards, is distinct enough to be plainly visible throughout its entire length, so that the precise line at which the lower edge of the next upper board is to be placed can be discerned. Both sides of every board should be marked, as shown at fig. 2, so that the best face and edge may always constitute, respectively, the outside-face and the lower edge, in their relations to the wall. One mark will usually answer, but it may sometimes be desirable to inscribe or mark two, or even three, so that there may be a greater or less extent of weather-surface or lap, at the pleasure of the builder, accordingly as varying circumstances may require an extension or diminution of the same.

Having thus described my invention, and pointed out its enormous economic merit in the saving of time that is at present absolutely lost in the practice of all existing and heretofore-known methods of accomplishing the same end, what I claim, and desire to secure by Letters Patent, is—The marking of weather-boards, in the manner herein described, during the operation of manufacturing them in the saw-mill, or afterwards, during the process of dressing them in the planing-machine, as and for the purpose set forth.

J. W. BAILEY.
